MINE CAR BEARING ASSEMBLY

William F. Dietrichson, Berwick, Pa., assignor to
American Car and Foundry Company, New
York, N. Y., a corporation of New Jersey

Application April 1, 1940, Serial No. 327,151

6 Claims. (Cl. 308—180)

This invention relates to mine cars in general and in particular to such cars mounted upon antifriction bearings and with the sills located outside the wheels.

The majority of early mine cars were built with the sills located between the wheels and with the bearings carried by the sills, thereby necessitating the wheels and axles to rotate either singly or as a unit with respect to the bearings. The present trend in mine car building is toward large capacity cars and to obtain proper stability and increased width it is preferable for the sills to be located outside of the wheels. It has been found that the most satisfactory location for antifriction bearings is in the wheel, thus giving freely rotatable wheels without the necessity of rotating the axle mass but in cases where the sills are located outside of the wheels it is difficult to adjust the bearings to compensate for wear. When adjustment for the bearings is provided by means extending through the sills, then these means are frequently damaged due to striking rocks or track side equipment. It is an object, therefore, of the invention to provide a means for adjusting wheel bearings through the outside sill and which means is protected by the sill itself.

A further object of the invention is the provision of an adjusting means for inside wheel bearings in which the adjusting threads are completely sealed to prevent their corrosion.

A still further object of the invention is the provision of a new and improved manner of locating the adjusting means provided for adjustment of the wheel bearing.

These and other objects of the invention will be apparent to persons skilled in the art from a study of the following description and accompanying drawing, in which:

Figure 1 is a sectional view taken through a portion of the mine car substantially at the axle line;

Fig. 2 is a sectional view taken substantially on line 2—2 of Figure 1, and

Fig. 3 is a sectional view taken substantially on line 3—3 of Figure 1.

Referring now to the drawing in detail, it will be seen that the improved bearing assembly has been applied to the side sill 2 of a car which may be of any desired type but is preferably of the type shown by Johnson Patent 1,555,982. The mine car sill 2 is supported on a support bearing or box 4 preferably made as a single casting with outstanding ears 6 and an upstanding flange 8 adapted to fit within a cut out portion of the side

sill to take side thrusts and thereby relieve the securing bolts or other means 10 extending through the sill and through the outstanding ears 6. The central portion of the bearing box 5 is provided with a vertically elongated opening 12 which is adapted to receive the axle end and associated parts. The axle 14 is supported by wheels W and extends outwardly beyond the wheels and into the bearing boxes which are supported thereon by means of a bearing adjusting sleeve 16. The antifriction bearings located in the wheels and supporting the axle on the wheel are shown as of the type manufactured by the Timken Bearing Company of Canton, Ohio, and comprise inner races 18, tapered rollers 19 and outer races 20. An inner dust collar 22 is shrunk on the axle, while an outer dust collar 24 closely engages the axle and is slidable therewith in order to move one of the inner raceways, thus permitting adjustment of the bearing. This outer dust guard collar is held in place and moved through its direct contact with the inner end of the bearing adjusting sleeve 16, the outer end of which bears against washer 26 or other suitable means.

Sliding movement of the dust collar 24, adjusting sleeve 16 and washer 26 is accomplished through the medium of a hexagonal headed bolt 28 having the shank 30 thereof externally threaded to engage with internal threads cut in an enlarged bore 32 drilled or otherwise formed in the end of the axle. The inner end of this bore is counterbored as at 34 to provide a portion of reduced area adapted to receive the inner end of a stub shaft 36. The inner end of this stub shaft is drilled to receive a pin 38 extending through the shaft and through holes bored transversely through the axle. This pin is of such a length, as clearly shown in Fig. 3, as to extend only through the axle and is thus held in position by the adjusting sleeve and in turn will prevent the rotation or removal of the stub shaft which will also be held substantially in alignment with the axis of the axle due to the projection of the shaft into the reduced bore 34. The outer end of the stub shaft which projects outwardly beyond the ends of the axle is slotted as at 40 in order to receive a pin or cotter 42 extending therethrough and through any one of the plurality of transverse openings formed in the bolt head. As clearly shown, the bolt has the shank and a part of the head thereof bored out as at 44 to receive the stub shaft 36. In order to prevent leakage of any moisture into the threads on the bolt shank and in the axle a felt

or other type washer 46 is interposed between the ends of the axle and the washer 26 and within the bearing sleeve 16.

It will be seen that by removal of the cotter or pin 42 the bolt head may be turned in either direction, thus applying force through the washer 26, adjusting sleeve 16 and dust collar 24 to the inner race of the bearing, thereby accomplishing adjustment of the bearing with a minimum of effort and while the car is either loaded or empty. Upon reinserting the cotter or pin 42 the adjustment will be retained since the stub shaft 36 is securely locked to the axle and cannot turn. It should be noted that the head of the adjusting bolt is slightly rounded and that substantially the entire bolt head is located beneath the sill and within the vertical plane of the outer face of the sill, thus minimizing the possibility of damage if the car should strike a rock or other track side obstruction.

While the invention has been described more or less in detail, it will be obvious that various modifications and rearrangements of parts may be made and all such modifications and rearrangements of parts are contemplated as will fall within the scope of the following claims which define my invention:

What is claimed is:

1. In an antifriction bearing including in combination, a shaft, a bearing raceway on said shaft interposed between an inner fixed member and an outer dust guard located at a point spaced from said shaft extremity, means for adjusting said raceway including a cylindrical element closely encircling said shaft extremity, the inner end of said cylindrical element normally engaging said dust guard and its outer end projecting beyond said shaft extremity, a bolt threaded into the end of said shaft having portions urging said cylindrical element against said raceway, and means axially positioned in said shaft for securing said bolt in adjusted position, the inner end of said last named means being secured by a pin confined by said cylindrical element against displacement and the opposite end by a transverse element extending into said bolt.

2. An adjusting means for bearings for wheels positioned inward from the ends of mine car axles of that type mounted for adjustment in bearing boxes to accommodate track inequalities and including in combination, a dust collar normally engaging a bearing element for adjusting movement therewith, cylindrical means slidable upon said axle and vertically shiftable with same in a bearing box, said cylindrical means bearing against said dust collar, means in threaded en-

gagement with the end of said shaft for engaging and adjusting said cylindrical means and bearings independent of said bearing box, and means for locking said last named means in adjusted position.

3. An adjusting means for bearings for mine car wheels of that type wherein the wheels are spaced between the side sills and in which the axle assemblies extend beyond said wheels, the combination of, a sealing element in adjustable engagement with said bearing, a cylindrical sleeve on said axle engaging said sealing element and extending beyond said axle extremity, said cylindrical element being slidable on said axle extremity and movable therewith, adjusting means in threaded engagement with the end of said axle normally engaging said sleeve element, a pin arranged in the end of said axle and extending into said adjusting means, the inner end of said pin being fixed and axially aligned by said axle structure and being secured in position in said adjusting means by removable securing means, and an axle box having a vertically elongated opening for permitting adjustment of said axle to accommodate track inequalities.

4. In a structure of the class described the combination of an axle, a box mounting the end portion of said axle for vertical adjustment, a wheel bearing assembly spaced inward of said box, a guard element in contact with said bearing assembly and positioned in adjustable relation on said axle for cooperation with said bearing assembly in the adjustment of the latter, a cylindrical element on the end of said axle extending beyond each side of said box, one end of said cylindrical element engaging said guard member and the opposite end of said cylindrical member extending beyond the axle, means engaging said axle and the projecting end of said cylindrical member to urge the latter axially of said axle to cause the adjustment of said bearing through said guard member, and locking means therefor.

5. The substance of claim 4 characterized in that the box is provided with a vertical elongated opening in which the axle and the cylindrical element are arranged for vertical adjustment.

6. The substance of claim 4 characterized in that the locking means includes a stub shaft extending into a counterbore in said axle, a pin locking said stub shaft to said axle, and a member extending through a part of said bolt to non-rotatably lock the shaft and bolt together.

WILLIAM F. DIETRICHSON.
